UNITED STATES PATENT OFFICE.

ISAAC HENDERSON, OF VANCOUVER, CANADA.

FREIGHT-HANDLING MACHINE.

SPECIFICATION forming part of Letters Patent No. 431,262, dated July 1, 1890.

Application filed August 1, 1889. Serial No. 319,371. (No model.)

To all whom it may concern:

Be it known that I, ISAAC HENDERSON, of Vancouver, in the Province of British Columbia and Dominion of Canada, have invented a new and Improved Freight Handling Machine, of which the following is a full, clear, and exact description.

The invention relates to hoisting and transporting machines; and its object is to provide a new and improved portable machine which is simple and durable in construction, very effective and automatic in operation, and specially designed for elevating, lowering, and transporting freight or other articles from, to, or into cars, ships, docks, &c.

The invention consists of an endless double track arranged vertically, or nearly so, cages adapted to travel on the said track, and conveyors connected with the ends of the said endless double track to move the articles to and from the said cages.

The invention also consists of certain parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a plan view of the improvement as applied to a vessel. Fig. 2 is a front elevation of the same, the vessel being in section. Fig. 3 is a side elevation of the same. Fig. 4 is an enlarged plan view of part of a sectional conveyor. Fig. 5 is a sectional side elevation of part of the improvement on the line $x-x$ of Fig. 1. Fig. 6 is a sectional plan view of the same on the line $y-y$ of Fig. 5. Fig. 7 is an enlarged transverse section of one of the conveyor-chains on the line $z-z$ of Fig. 5. Fig. 8 is an enlarged face view of part of the endless double track and carrier-chains; and Fig. 9 is a sectional plan view of one of the tracks and chains.

The improved freight-handling machine is provided with two endless tracks $A A'$, running nearly parallel with each other, and on which are held to travel the endless carrier-chains $B B'$, respectively, supporting the cages C , placed suitable distances apart on the said chains. The upper and lower ends of the tracks $A A'$ are connected with conveyors D

and E , alike in construction and serving to carry the articles to be loaded on or unloaded from the said cages C . The endless chains $B B'$ in the tracks $A A'$ are set in motion by endless chains F , or other mechanism driven by suitable machinery located on the dock or vessel.

The endless tracks $A A'$ are secured on two upright beams A^2 , connected with each other at the top and bottom by cross-pieces A^3 and A^4 , and also connected at intermediate points, according to the height of the beams. The tracks $A A'$ are twisted and curved to face the beams A^2 at one end and the back at the other end, forming an endless double track, the upright portions of which join each other, twin fashion, (see Fig. 8,) while the horizontally-curved portions lie equal distances apart in a vertical or approximately vertical line equal in length to the distance between the centers of the pivots of each cage C .

The tracks $A A'$ form equal channels for the chains $B B'$, and each channel is provided with a back or bottom piece A^5 , which is U-shaped in cross-section, as is plainly shown in Fig. 9. From the back A^5 extend the sides A^6 , supporting the two face-pieces A^7 , forming a slot A^8 .

The endless track or carrier-chains $B B'$ are more fully illustrated in detail in Figs. 5, 6, 8, and 9, and each consists of a series of forked links B^2 and B^3 , pivotally connected at their open ends by pins B^4 , extending parallel to the sides A^6 of the track and passing through both ends of the forks, which are hubbed and eyed for this purpose. A wheel B^9 is journaled on the said pin B^4 between the prongs of the forks and is adapted to run on the projection A^9 , formed on the back A^5 of each track, when the track and chain run horizontally, or nearly so, and the back of track is in a vertical position. One of the prongs of each link is formed and connected with the other in a straight line, and is provided at its inner edge with one or more notches B^{10} , placed at regular intervals and adapted to be engaged by the cross-pins of the endless chains F , which impart motion to the chains B and B' . The other end of each link is journaled upon an axle B^5 , placed at right angles to the pin B^4 and carrying a wheel B^6 , journaled at each end thereof.

Each wheel B⁶ (see Fig. 9) travels between the inner surface of the back A⁵ and the face pieces A⁷ of the tracks A and A'. Each axle B⁵ is thus held by two link ends, one of which 5 is sheared out to receive the other and form a joint, of which the axle forms the pin or pivot. Each chain B and B' is also provided at suitable intervals with a stud B⁷, extending outward from the center of one axle end 10 of link. On each stud B⁷ is mounted to turn a wheel B⁸, traveling in the slot A⁸, with its periphery on the edges of the face-pieces A⁷ of the tracks A A', as is plainly shown in Figs. 5 and 6. The outer end of each stud B⁷ also 15 forms one of the pivots for a cage C. Each chain B or B' is capable of bending to adapt itself to compound curves, or curves at right angles to each other, and the axle-joints are made to allow chain to twist—say one-quarter 20 turn in about six feet. The diameter of the wheels B⁶ and the length of the axles B⁵ are proportioned to the cross-sections of the tracks A and A'.

The endless chains F, for imparting a traveling motion to the endless chains B and B', pass over suitably-shaped sprocket-wheels F' 25 and F², fastened on the shafts F³ and F⁴, respectively, mounted to turn in suitable bearings in the beams A², supporting the tracks A and A'. The front parts of the chains F extend onto the back A⁵ of the tracks, said back being cut away a suitable distance to admit the chains and the wheels F' and F², as 30 is plainly shown in Figs. 5 and 6.

35 Each cage C is provided with a number of bars C', diverging from the center of the top and secured to a cross-bar C² below, from which they are bent to project at right angles to the plane to form a bracket with a grated 40 floor consisting of a series of arms C³, adapted to pass freely through a correspondingly-grated end of the conveyers D and E. In the middle of the cross-bar C² and extending rearward is formed a hub C⁴, fitting onto the studs 45 B⁷, carrying the friction-wheel B⁸, previously mentioned, and projecting from one of the links of the endless chains B B'. On the upper ends of the diverging bars C' is formed a second hub C⁵, fitting loosely onto the corresponding studs B⁷ of the other endless chain B' or B. As is plainly shown in Fig. 3, the 50 upper hub C⁵ of each cage C is thus journaled in the upper or outer chain B, while the lower hub C⁴ is journaled on the inner or lower chain B'. The cages are secured in place by 55 passing a pin through each stud B⁷ just in front of the hub C⁵, as shown in Fig. 5.

Each of the conveyers D or E is provided with a series of parallel tracks G, connected 60 with each other at suitable intervals on the bottom of the cross-piece G'. In the top of each track is formed a groove G², in which is mounted to travel a chain H, the top edge of which extends a suitable distance beyond the outer edge of the respective track, as is plainly 65 shown in Figs. 5 and 7. From the bottom of the groove G² extend upward and sidewise

openings G³ to permit the grit and other impurities collecting in the groove G² to pass to the outside, so as not to obstruct and clog the 70 chains H. The said chains H pass over pulleys H' at each end of the tracks G, said pulleys being secured on separate and independent shafts H², mounted to turn in suitable bearings at the extreme ends of said tracks G. 75 These pulleys H' at the inner ends of the tracks form the inner extremity of the conveyer, and as the pulley-shafts are separate and independent the inner ends of the tracks are disconnected, which permits the grated 80 cages to pass therethrough with their vertical rear walls close to said pulleys. The chains H of each conveyer are driven by sprocket-wheels I, secured on a shaft J, mounted to turn in suitable bearings in the tracks G. On 85 the shaft J of the conveyer E is secured a sprocket-wheel J', over which passes a sprocket-chain K, extending to the dock or along the vessel and driven by suitable machinery, so as to rotate said shaft J. The latter also 90 carries a second sprocket-wheel J², over which passes a sprocket-chain L, also passing over a sprocket-wheel F⁵, secured on the shaft F⁴, previously mentioned, and carrying the wheel F², over which pass the endless chains F, imparting a traveling motion to the chains B and B'. On the shaft F⁴ is also secured a bevel gear - wheel N, meshing into a bevel gear-wheel N', secured on a shaft N², mounted to turn in suitable bearings on the beams A² 95 and carrying a sprocket-wheel N³, over which passes a sprocket-chain N⁴, extending downward between the said two beams A², and also passing over a sprocket-wheel N⁵, secured on a shaft N⁶, mounted to turn in suitable 100 bearings on the cross-beam A³ connecting the beams A² with each other at their lower end. On the shaft N⁶ is secured a second sprocket-wheel N⁷, over which passes a sprocket-chain N⁸, also passing over a sprocket-wheel N⁹, secured on the shaft J of the conveyer D. (See 105 Figs. 1 and 2.) Thus when the shaft J of the conveyer D is turned the machine is set in motion.

Each conveyer may be made in short sections, as shown in Fig. 4, in which the pulleys of the adjoining ends of each section are mounted on a common shaft H³, and on these shafts are mounted sprocket-wheels O, over 110 which pass sprocket-chains P, so that when one set of chains H is caused to travel their motion is transmitted to the other set by the wheels O and chains P. (See Fig. 4.)

The operation is as follows: When the machine is used for unloading a vessel, for instance, the beams A², supporting the tracks A and A', are set in the hold of the vessel in a vertical or approximately vertical line, the upper cross-beam A⁴ resting on a beam Q, held across the hold of the vessel, as is plainly 115 shown in Figs. 1 and 2, so that the said beams with the tracks are suspended on the vessel. The conveyer D is placed in the hold of the vessel, one end extending to within a short 120

distance of the lower ends of the beams of the tracks A and A', so that the arms C³ of the cages can pass between the chains H and the tracks G. In a similar manner the conveyer 5 E is connected with the upper ends of the tracks A and A', as is plainly shown in Fig. 3. The cages in this case pass with their arms C³ down through the end of the conveyer E and pass upward through the end of the conveyer D. When the machine is set in motion, as previously described, by imparting a traveling motion to the chain K, then the endless chains B and B' are caused to travel on the tracks A A' in such a manner that the 15 cages C pass down on one side of the double track and come up on the other. Merchandise or other articles to be unloaded from the hold of the vessel are placed on the chains H of the conveyer D, so that the said chains 20 carry the merchandise forward to the tracks A and A', and when the next cage C passes upward from below its arms C³ take hold of the merchandise and carry it upward and over the upper ends of the tracks, then downward to deposit it on the chains H of the conveyer E. The arms C³ of the respective cages 25 pass between the ends of the conveyer E and leave the merchandise on the chains H, and the latter carry the same to the dock or wharf 30 or other desired place. When it is desired to load the vessel, the driving machinery is reversed, so that articles placed on the chains H of the conveyer E at the outer end of the latter are moved to the tracks A and A', and 35 then carried downward by the cages C to the conveyer D, which latter movesthem along the hold of the vessel to any desired place in the same.

Having thus fully described my invention, 40 I claim as new and desire to secure by Letters Patent—

1. In a freight-handling machine, a grated conveyer consisting in parallel tracks having pulleys journaled separately on their ends, 45 and endless conveyers passing around the tracks and pulleys, substantially as set forth.

2. In a freight-handling machine, a grated conveyer consisting in the parallel tracks G, disconnected at their delivery ends and 50 grooved longitudinally on their upper faces, as at G², and having the pulleys H' on separate shafts H² at the ends of said tracks, and the endless chains passing through said grooves and around the pulleys, substantially 55 as set forth.

3. In a freight-handling machine, the conveyer having longitudinally-grooved tracks G, provided with lateral apertures G³ intersecting said grooves, the separate and independent pulleys, and the endless conveyers extending through said grooves around the pulleys, substantially as set forth.

4. In a freight-handling machine, the combination, with the parallel tracks having pulleys on their extremities and the endless conveyers passing around the same and forming a grated conveyer, of the endless elevator-

chains, the grated cages, the outwardly-projecting fingers or arms of which are adapted to pass between the grated conveyer, the pulleys on the several tracks extending close to the inner ends of the said arms or fingers, substantially as set forth. 70

5. The combination, with the endless carriers or elevator-chains, of cages secured at 75 their upper ends to one elevator-chain and at their lower ends to the other, substantially as set forth.

6. The combination, with the endless carriers or elevator-chains having their upper 80 and lower end portions extending parallel with each other and facing in horizontal planes approximately at right angles to their intermediate portions, of a cage or carrier secured at its upper end to one carrier or elevator-chain and at its lower end to the other, 85 substantially as set forth.

7. In an apparatus of the character set forth, an endless double track twisted between its ends and having the upper and 90 lower ends of its two parts facing horizontally and spaced apart as shown, substantially as described.

8. The combination, with an endless double track twisted between its ends and having 95 its upper and lower ends facing horizontally and spaced apart, of the separate and independent endless carrier-chains traveling along said tracks, and a cage or receptacle secured at its upper end to one carrier-chain 100 and at its lower end to the other carrier-chain, substantially as set forth.

9. The combination, with the endless tracks A A', having their upper and lower ends facing horizontally in opposite directions and 105 spaced apart, of the endless chains, independent one of the other and traveling along said tracks, and the cage or receptacle secured at points one above the other to said chains, substantially as set forth. 110

10. The combination, with the parallel connected uprights A² and the endless tracks A A', twisted and curved to face the beams at one end and the back at the other end and forming an endless track, the upright portions of which join each other, while the horizontally-curved end portions are spaced vertically apart, of the endless carrier-chains traveling around said tracks and provided with studs or pivots spaced apart the same 115 distance as the horizontally-curved end portions of the tracks, and the cages or receptacles secured to said pivots or studs, substantially as set forth. 120

11. In a freight-handling machine, the combination, with a track forming a channel, substantially as described, of a chain adapted to travel in the said channel and comprising a series of links each made in two parts and provided with notches for engagement with 125 the driving mechanism, a pin connecting the two parts with each other, axles standing at right angles to the said pins and connecting successive links with each other, and friction- 130

wheels carried on the said axles and adapted to travel on the inner surfaces of the front and back of the said channel, substantially as shown and described.

12. In a freight-handling machine, the combination, with a track forming a channel, substantially as described, of a chain adapted to travel in the said channel and comprising a series of links each made in two parts and provided with notches for engagement with the driving mechanism, a pin connecting the two parts with each other, axles standing at right angles to the said pins and connecting successive links with each other, friction-wheels carried on the said axles and adapted to travel on the inner surfaces of the front and back of the said channel, and a friction-wheel held on the said pin and adapted to travel on an offset in the said channel when the track and chain run horizontally, or nearly so, substantially as shown and described.

13. In a freight-handling machine, a conveyor comprising a series of parallel tracks provided with grooves in the top, endless chains held to travel in the said grooves, and means for imparting motion to the said endless chains, in combination with cages mounted to travel and provided with a grated bottom formed by arms adapted to pass between the said chains and tracks at their ends, substantially as shown and described.

14. The combination, with the upper and lower endless conveyers at right angles to each other, of the uprights A² and the endless tracks A A', twisted and curved between their ends along the beams, their ends being horizontal and spaced vertically to bring the tracks in proper relation to said conveyers, and the separate and independent endless chains in said tracks, and the cages secured at their upper ends to one chain and at their

lower ends to the other to pass the said conveyers vertically without overturning, substantially as set forth.

15. In an apparatus of the character described, an endless carrier-chain comprising a series of links, each made in two parts and provided on their inner edges with notches for engagement with a driving mechanism, a pin connecting the two parts with each other, 45 and other pins or axles at right angles to the first-named pins and connecting the successive links together, substantially as set forth.

16. In an apparatus of the character described, a carrier-chain comprising a series of 55 links made in two parts notched on their inner edges, a pin connecting said parts of each link with each other, axles at right angles to said pins and connecting the said two-part links together, and friction-wheels on said 60 axles and pins, substantially as set forth.

17. In an apparatus of the character described, the carrier-chain comprising a series of links made in two parts notched on their rear edges and one of said parts on certain of 65 the links having studs B' projecting from their front edges, pins connecting the two parts of said links, friction-wheels on the inner portions of said pins, and axles connecting the successive links at right angles to 70 said pins and provided with friction-wheels, substantially as set forth.

18. The combination, with an upright frame, of double endless track curved and twisted to 75 pass from front to back of the frame and through vertical and horizontal positions, substantially as shown, and for the purpose described.

ISAAC HENDERSON.
